Attest.

JEROME B. SWEETLAND, OF PONTIAC, MICHIGAN.

Letters Patent No. 83,566, dated October 27, 1868.

IMPROVEMENT IN WASH-BOILERS.

The Schedule referred to in these Letters Patent and making part of the same.

To all whom it may concern:

Be it known that I, JEROME B. SWEETLAND, of Pontiac, in the county of Oakland, and in the State of Michigan, have invented certain new and useful Improvement in Boilers for Washing Clothes and Boiling Vegetables; and do hereby declare that the following is a full, clear, and exact description thereof, reference being had to the accompanying drawings, and to the letters of reference marked thereon.

The nature of my invention consists in the construction and general arrangement of a boiler, suitable for washing clothes, as well as for boiling and washing vegetables, roots, &c.

In order to enable others skilled in the art to which my invention appertains, to make and use the same, I will now proceed to describe its construction and operation, referring to the annexed drawings, which form a part of this specification, and in which—

Figure 1 is a side elevation, in section, of the boiler complete, and

Figure 2 is a side elevation, in section, of the reversed bottom.

A represents a common boiler, with a sunken bottom, although it may be made of any shape desired.

Inside of this boiler I place another boiler-bottom, B, turned upside down, which reversed bottom has a metal rim, C, put on the flange, projecting downwards any desired distance, and which rim is provided with a small flange, a, around its lower edge.

The reversed bottom B, thus constructed, rests on that part of the bottom of the boiler A which is not turned down, as shown in fig. 1, and is secured to the same by means of two lugs, b b, in the boiler A. A small slot in the flange a allows said flange to be put under one of these lugs, and the other extending up through the slot mentioned. By then turning the bottom, B, a little, the lugs b b will hook the flange a, and hold the reversed bottom tightly.

When the pressure of steam comes on the reversed bottom, these lugs will hold the bottom just as firm, with all the strain there will ever be on it, as though it were soldered fast.

The rim C is provided with one or more holes, which are covered with valves D D, on the inside, so that when the pressure of water on the outside is greater than the resistance of the pressure on the inside, after the water has been thrown out from the inside, then the valves D D open, and the vacuum fills with water, and the least pressure from the inside closes the valves, which hang naturally almost tight.

In the centre of the reversed bottom, B, is a circular opening, over which I place a cone-shaped tube, E, the wider end being provided with a flange, c, which rests on the bottom, B. The flange c is provided with two or more notches, and on the bottom, B, is placed a corresponding number of lugs or keys, d d. By placing the tube E so that each key fits into its notch on the flange c, and then slightly turning the tube, said keys catch on the flange and hold the tube firmly.

The upper smaller end of the tube E is also provided with a flange, e, which is grooved on its under side, and on this flange a cap, F, is placed, which cap, being provided with two or more pins, f f, bent and fitting into the groove on the flange e, forms a loose joint. The upper end of the cap, F, is secured to the horizontal pipe G, one or both ends of which may be loose, so as to allow contraction or expansion at will. The ends of the pipe G are closed, and from the side near the ends are spouts, H H, through which the hot water will pass out.

When the steam and water are forced out through the horizontal pipe G and spouts H H, the reaction of the water causes the pipe G to turn in the opposite direction from which the water comes out of the pipes, of its own accord.

On top of the reversed bottom B is a wooden rack, I. This rack is provided with a circular hole in the centre, through which the tube E projects, and near its outer periphery it is provided with a series of smaller circular holes to allow the water to pass through.

Through the centre of the reversed bottom, B, I place a partition or wall, J, which partition extends downwards from the centre of the top of said bottom, and is provided at its upper end with a hinged pallet or valve, L, extending upwards in the tube E. This pallet or valve is of such a shape that, when turned to either side, it will effectually close that side of the tube.

When the reversed bottom, B, is fastened tight to the bottom of the boiler, the partition J should be so arranged as to fit tight all around, and if the boiler has a sunken bottom, the partition will go down into it, as shown in fig. 2, and fit tight.

When, now, the water in one side of the boiler gets hot enough to start, the first thing it will do will be to close the valve D, then there is no escape only as it goes up the pipe E, and in order to get up this pipe it has to throw the pallet L over to the opposite side, thus preventing the water and steam from going over into the other side. While the first side is running, the water has free access to the other side, through its valve D, and immediately fills, and as soon as the water is thrown out of one side, by that time the opposite side is full of steam, and will throw the pallet L to the opposite side, and that side will fill.

By this arrangement, I save all the force for doing the work, and have a double-acting boiler, so that when one side is running, the opposite side is filling, thus keeping up a steady, strong stream of water, and steam pouring on to the clothes or vegetables, as the case may be.

Having thus fully described my invention,

What I claim as new, and desire to secure by Letters Patent, is—

1. The reversed bottom, B, provided with a rim, C, projecting downwards, and said rim provided with openings, covered on the inside with valves D D, substantially as and for the purposes herein set forth.

2. The removable cone-shaped tube E, secured to the

reversed bottom, B, by means of the notched flange *c* and keys *d d*, or its equivalents, and provided at the top with a grooved flange, *e*, on which is placed the cap, F, with its lugs *ff*, forming a loose joint, substantially as and for the purposes herein set forth.

3. The reversed bottom, B, provided with a partition or wall, J, and hinged pallet or valve L, the lat-

ter extending up into the tube E, substantially as and for the purposes herein set forth.

In testimony that I claim the foregoing, I have hereunto set my hand, this 12th day of September, 1868.
